PLATE CLAMP

Jack Bryer, Paramus, N.J., assignor to R. Hoe & Co., Inc.,
New York, N.Y., a corporation of New York
Filed Sept. 23, 1958, Ser. No. 762,841
5 Claims. (Cl. 101—415.1)

This invention relates to plate clamps for holding printing plates on printing cylinders, and more particularly for use with lithographic printing plates or other comparatively thin, flexible plates.

It is an object of the invention to provide a plate clamping mechanism of simple construction and requiring a minimum opening or gap in the cylinder surface for the insertion of the plate end.

It is another object of the invention to provide for a mechanism which permits an easy removal of the plate from the plate cylinder surface by pushing the tail of the plate out of the opening or gap of the cylinder when opening said clamping mechanism.

A plate clamping mechanism embodying the invention in a preferred form will now be described with reference to the accompanying drawing, and the features forming the invention will then be pointed out in the appended claims.

In the drawing:

FIG. 1 is an approximately axial section, taken on the line 1—1 of FIG. 3, of the plate clamping portion of the printing cylinder;

FIG. 2 is a section on the line 2—2 of FIG. 1, showing the operating mechanism;

FIGS. 3 and 4 are sections on the lines 3—3 of FIG. 1 and showing the parts in two different positions.

The plate clamping mechanism is carried in a rectangular groove or channel 1 which is formed in the cylinder body 2 in the usual way. The mechanism comprises a supporting block 3 fitting in this groove and having a bore 4 which accommodates a plate clamping rod or shaft 5, the rod having clearance in the bore sufficient to accommodate the plate P and being supported in the bore by means of bearer rings 6 which are fixed to the rod 5 as by screws 7 and extend about two-thirds around the circumference of the rod so as to furnish the necessary support while not interfering with the plate.

A gap 8 is cut in the cylinder surface and into the bore 4 to accommodate the plate. This gap has on one side a rounded edge 9 to take the end 10 of the plate and this rounded edge connects to the surface of the bore 4 by a tangential plane surface 11, as shown in FIGS. 3 and 4. The other side of the gap comprises a somewhat rounded edge 12 which is positioned substantially tangent to a plane which is tangent to the rod 5 at approximately the point where the plane 11 joins the inner surface of the bore 4. The rod 5 has a longitudinal groove 13 accommodating a clamping plate 14, which is supported on plungers 15 carried in the rod 5 and movable diametrically thereof. The rod is bored, as indicated in FIGS. 3 and 4, having a smaller bore 16 adjacent the groove 13, which accommodates the plunger 15 and a larger bore 17 which accommodates the enlarged head 18 of this plunger and also receives a spring 19 thrusting against the head 18 and against the end of the bore 17. The bore 4 is cut back as indicated at 20 to form a recessed cam surface receiving the plunger head 18, so that in the unlocked position of FIG. 4, the clamping plate 14 may be drawn down against the bottom of the groove 13, while in the locked position of FIG. 3, this clamping plate will be moved up in the groove 13 for holding a plate end as described below. The groove 13 has a straight wall 21 against which the clamping plate 14 slides and an undercut beveled wall 22 which is parallel to the correspondingly beveled face 23 of the clamping plate 14, the sur-

2

faces 22 and 23 forming cooperating plate end engaging jaws.

In operation, the plate ends are pre-bent to the form shown in FIG. 4, the end 10 being bent around so as to fit over the rounded edge 9 on one side of the gap and lie against the plane surface 11, as indicated, and the other end 26 being bent at an acute angle, as indicated at 25, and the edge portion 27 being of such length as to insert readily in the gap and hook over the edge of gap 13, as indicated. It will be observed that the width of the gap 8 may be very narrow and need be only sufficient to accommodate the bent edge 25, which may be sprung slightly in passing through the narrowest point of the gap. With the parts in the position of FIG. 4, the plate end 10 is first hooked over the gap edge 9 and the plate is pulled around into approximately the position of FIG. 4. Thereafter, the bent edge 25 is pushed into the cylinder gap until the edge section 27 hooks in back of the edge of groove 13, behind the undercut gap wall 22. Rotation (clockwise) of the bar 5 pulls the edge of the gap 13 into the inside of the plate bend 25, drawing the plate end around with the bar and under the other end 10 of the plate, where it lies against the flat surface 11. During this rotation, the head 18 of plunger 15 rides up on cam surface 20, thus pushing up the clamping plate 14 until it engages the plate end 27, as indicated in FIG. 3. Thereafter, as the turning continues, the plunger head 18 rides against the concentric surface of the bore 4, holding the plate end within the groove 13, as shown in FIG. 3, so that the plate is stretched around the cylinder and the required tension for holding it in position is developed. The edge 28 of the other end of the plate is spaced from the surface of bar 5 by approximately the thickness of the plate, so that the portion 26 which is pulled around on the bar in locking up the plate and which is very nearly tangent to the flat surface 11, locks the other plate end 10 securely in position.

The mechanism for operating the bar 5 to lock and unlock the plates, comprises a worm wheel 30 fixed to the bar 5 and operated by a worm 31 which is fixed to a shaft 32 which is rotatable and slidably in sleeve elements 33 and 34, which are fixed in a bore 35 in the cylinder body 2 and clamping assembly body 3, frustoconical or "Belleville" spring elements 36 acting between the worm 31 and sleeve 33 force the worm down in the position of FIG. 2. The shaft 32 is provided with a wrench socket 37 to permit turning the shaft for locking and unlocking the plate. Starting in the position of FIG. 4, the plate end 27 is inserted in the gap 13 as previously mentioned, and the worm shaft 32 is rotated so as to bring the parts into the locked up position of FIG. 3. During this movement, the worm wheel remains in its lower position on the shaft 32, until the plate is tensioned. Further rotation of shaft 32, by reason of the helical pitch of the worm teeth, will cause the worm and shaft 32 to move axially outward against the spring 36, the visible protrusion of the end of shaft 32 thus indicating that the tensioning rotation of the bar 5 has been completed, and avoiding damage due to inadvertent application of excessive force on the wrench. The Belleville spring also acts as "take-up" mechanism if the plate should stretch after a period of operation.

As pointed out above, the insertion of the angle 25 involves merely pushing it into the gap 8, the acute-angled edge of the reel rod or shaft groove 13 automatically taking hold of the edge 27 as the reel rod is rotated from the position of FIG. 4 to that of FIG. 3. Similarly, as the rod is rotated back from the position of FIG. 3 to that of FIG. 4 to disengage the plate, the edge 27 by reason of the plate stiffness is automatically backed out of the groove 13 and passes through gap 8 with no difficulty.

What is claimed is:

1. A printing cylinder plate clamping mechanism comprising a cylinder body having an axial bore adjacent its surface and an axially extending gap communicating with the bore, a reel rod fitting the said bore, having a groove and clamping member within the groove for holding the printing plate end, and operating means for the said clamping member comprising spring means for urging the clamping member toward open position and cam means for forcing it into closing position, the last 10 said means comprising a plunger mounted diametrically in the said reel rod and a cam surface formed in the wall of the said cylinder body bore, whereby rotating the reel rod to a plate end receiving position with relation to the said gap permits the said spring means to open the clamping member and rotating it away from the said position causes the said cam surface to close the said clamping member.

2. A printing cylinder plate clamping mechanism according to claim 1, in which the said reel rod groove 20 has an inwardly diverging wall for receiving a plate end bent to an acute angle around the adjacent edge of the groove, and the plate gap has a lesser width than the plate edge bent to the said angle, whereby the pre-bent edge may be sprung through the gap and into the said groove.

3. A printing cylinder plate clamping mechanism according to claim 2, comprising a plate end supporting surface extending from an edge of the gap tangent to the bore, whereby a plate end held in the said reel rod groove 30

engages against an opposite end of the plate, forcing the same against the said tangent surface for holding it in position.

5 4. A printing cylinder plate clamping mechanism according to claim 3, in which a continuation of the said tangent surface clears the other side of the gap by about twice the thickness of the plate.

5 5. A printing cylinder plate clamping mechanism according to claim 4, in which the said plunger engages a concentric cylindrical portion of the cylinder body bore in clamping position and the said concentric cylindrical portion extends beyond the point of said engagement to permit further tightening, and comprising yielding means for holding the reel rod in plate clamping position with predetermined pressure, whereby the angular position of the reel rod may vary without varying the clamping action.
